UNITED STATES PATENT OFFICE.

WARREN E. COLLINS, OF JAMAICA PLAIN, MASSACHUSETTS.

MOTOR BLOWER UNIT FOR METABOLISM APPARATUS OR THE LIKE.

Application filed February 7, 1925. Serial No. 7,699.

To all whom it may concern:

Be it known that I, WARREN E. COLLINS, a citizen of the United States, residing at Jamaica Plain, county of Suffolk, Commonwealth of Massachusetts, have invented certain new and useful Improvements in Motor Blower Units for Metabolism Apparatus or the like, of which the following is a specification.

10 This invention relates to blowers and particularly to such devices used for the circulation of oxygen or other gases where desired degree of pressure is of great importance and where the purity of the gas handled is a prime requisite. As illustrative of such usage and as indicative of the exhaustive character of the requirements I will discuss my invention in connection with apparatus used in metabolic experiments and tests. Such use is, of course, to be considered merely as illustrative as my blower has been developed in connection with my metabolism apparatus.

As is well known such tests as those involving the use of oxygen in connection with respiration necessitate apparatus of the most delicate character whether the test be merely physiological as in the diagnosis of certain diseases or whether this be complicated by use in connection with psychological tests in which the effects of mental activity are studied through such metabolism. In these tests as indicated above, it has been found necessary to circulate the gas in such a way that the patient will be undisturbed or distracted and be relieved of respiratory labor and the gas will be handled without the slightest possible contamination, especially from any source involving carbon.

40 The construction of such apparatus is therefore highly specialized but nevertheless is capable of other uses whether of the same degree of exacting requirement or of a less exacting demand.

45 As illustrative of my invention I have shown in the accompanying drawing a blower apparatus which I have found well adapted to use and which I will now proceed to describe in connection with the accompanying drawings. Throughout the

specification and drawings like reference characters are employed to indicate corresponding parts, and in the drawings:

Fig. 1 is a plan view of an apparatus in accordance with my invention. 55

Fig. 2 is a side view thereof, partly broken away to disclose internal structure.

Figs. 3 and 4 are end views of the motor and blower ends respectively.

Fig. 5 is a somewhat diagrammatic view 60 of an installation with my motor.

Fig. 6 is an enlarged section of my fan bearing and packing, and

Fig. 7 is a view of an impeller blade and shaft removed. 65

In these drawings I have indicated at 1 a blower casing of shallow cylindrical form having an exhaust 2 adapted to be connected to any desired apparatus. One of the lateral walls 1¹ is apertured as at 3 for intake being provided with an annular flange 3¹ surrounding said opening in which is located a compressible washer 4 against which the end of one arm of an elbow 5 finds bearing. The opposite end of the elbow 5 is connected with a suitable nipple 5² which may be attached to any kind of an intake connection, as for example, a rubber hose leading from a respiration apparatus. 70

The elbow 5 is adjustably held within the flange 3¹ and against the washer 4 by a stem 6 on the outer end of which is threaded an adjusting nut 7 contacting with a bearing 5¹ formed on the curve of the elbow so as to be aligned with the central axis of the contacting arm. The stem 6 is held in a cross piece or spider 8 left across the intake opening 3 being threaded therein and held by a lock nut 9 so as to be adjustable therethrough. 75

The stem extends through this ridge or spider in alignment with the fan shaft 10 and is adapted to be adjustably brought into contact with the end of said shaft for adjustment as hereinafter described. 80

Opposite the intake opening the side 1² of the casing is provided with an elongated bearing 11 extending well within the casing and having an outside portion 11¹ in which any suitable oiling device as 12 is mounted. This oiling device connects with a stuffing 85 100

box 13 of any suitable type surrounding the shaft 10.

The fan shaft 10 is connected by any suitable coupling 14 providing slight play or adjustment of the shaft 10 relative to the motor shaft 15 of the motor M. On the bearing 11 is a cup shaped hub 16 the outer end of which is threaded to the shaft 10 and held by the lock nut 17 so that the hub 16 is fast on the shaft 10 by which it is driven.

At its inner end the hub 16 is provided with an outturned flange to which is fastened the fan member 18. This member 15 may be variously formed but is preferably of channel shape, comprising a rear wall and two side walls. Its front side may also be closed forming a more or less complete tube opened adjacent its center and 20 opposite the intake, or the fan may be formed entirely open on its front side. This fan member in such a device is very light, preferably being made of thin aluminum stock and as a result of its 25 balance and its efficient shape, the motor is able to carry a maximum circulation at a minimum of speed by which noises are avoided which otherwise might interfere with delicate tests or experiments in which 30 the apparatus is involved.

Between the hub 16 and the end of the bearing 11 I interpose packing or washer 19. This washer is preferably of a fibrous or absorbent material and preferably one 35 having considerable elasticity. For this purpose I may employ a felt or like material. This simple feature is of great practical importance as a check to the oil which tends to be drawn through the bearing 11 by the 40 suction of the fan. Should any such oil or residue thereof be actually drawn into the blower, the accuracy of the test might and probably would be lost. It is, therefore, important to withhold this oil while 45 allowing its full lubricative action for the full length of the bearing. This packing 19 is held under slight compression by the end of the stem 6 which bears upon the end of the shaft 10, thus forcing the inner face of 50 the hub 16 against the packing, making an oil and air tight joint. Any oil reaching this packing is either checked by it or if drawn under or around the shaft it is 55 caught up by the powerful capillary action of this fibrous material and thus held during the test or experiment. These packings can be frequently replaced in order to maintain their efficiency.

The motor M is provided with a pair of feet 20 and the blower with a single foot 21 thus giving a three point suspension form of support to the apparatus. About these feet I slip tubular shoes S of rubber or like material. This not only affords a cushioning support but permits a slight adjust-

ment of the motor and blower on any mounting on which they are held by the bolts 22.

The motor is preferably rigidly coupled to the blower casing as at 24 by tie rods 70 so as to hold the parts aligned and prevent vibration.

As above explained, my construction is of great advantage in connection with metabolism apparatus or the like, and I 75 have, therefore, shown in Fig. 5 a somewhat diagrammatic view indicating its location and connection with such apparatus. In such apparatus I have indicated the motor and blower by their characters assigned 80 above. The soda lime tank I have indicated at T with the connection 23 between the exhaust 2 of the blower and the intake of the apparatus. This is simply a short piece of pipe or hose connecting these nipples 2 and 23. The connection 25 passes from the outlet of the tank to the respiratory apparatus R of whatever form is to be used. The return 26 leads from the mouthpiece R back to the intake of the 85 blower 1.

With such an installation as this, it will be seen that the blower is called upon for a most exacting performance. Not only must the oxygen which is being supplied to 90 the patient be conserved, but it must be preserved against dilution by leakage of air. Further, as above described, it must not be contaminated as the scientific results of the 95 test would be rendered utterly unreliable. 100

This is one of the vital features of my invention and is one of the reasons for my conception of the elongated bearing 11 and the packing under the hub. There is, of course, with all blowers, a tendency to draw 105 in air about the main bearing, but in the ordinary blower such leakage does no harm at all. My elongated bearing is, therefore, of very great importance as a check on such leakage, especially in its combination with 110 the absorbent compressible washer 19 which not only checks any leakage of air or in-drawing of oil, but anticipates the same by reason of its location, which is so far advanced as to be almost in the intake of the 115 blower. Furthermore, the long bearing makes the blower very steady, and in its relation to the light hollow fan blades permits a speed of from 4000 to 7000 R. P. M. 120 without creating any disturbing vibration.

The motor blower unit can be set up on an ordinary table or stand with the rest of the apparatus right at the bedside of the patient and can be quickly removed and passed on to other patients or stored, as may 125 be desired.

While I have described my above structure in some detail as to its various points of desirable improvement, it will be understood that these elements may be variously 130

employed and combined and the apparatus may be variously connected for whatever purpose or use it may be desired, and all without departing from the spirit of my invention if within the limits of the appended claims.

What I therefore claim and desire to secure by Letters Patent is:

1. In a blower of the class described, a casing, an elongated bearing extending within said casing, a shaft through said bearing, a cap shaped fan hub mounted on said bearing and attached to said shaft, a compressible member disposed between the end of said bearing and said fan hub and disposed about said shaft, and means for adjusting said hub against said member.
2. In a blower of the class described, a casing, an elongated bearing extending within said casing, a shaft through said bearing, a fan hub mounted on said bearing and attached to said shaft, a compressible packing member disposed between the end of said bearing and said hub and about said shaft, and means for adjusting said hub against said member.
3. A blower of the class described, comprising a casing, an intake opening centrally of said casing, an intake elbow rotatably disposed over said opening, an adjusting stem disposed through said elbow axially of

its arm, and an adjustable clamping member threaded on said stem for holding said elbow arm against said casing, and a fan shaft rotatably mounted in said casing, a hub on said shaft, and a packing behind said hub said stem being aligned with said shaft and in adjusting contact therewith.

4. In a fan of the class described, a casing having an intake, a blade member rotatably mounted in said casing, said member comprising back and side walls defining a channel longitudinally of the blade, and having an open side disposed towards said intake.

5. In a fan of the class described, a casing having an intake, a blade member rotatable therein, said member having an arm channel longitudinally of the blade, and having an open side disposed towards said intake.

6. In a fan of the class described, a casing having an intake, a hub and a blade member attached to said hub, said member comprising a shaft rotatably mounted in said casing, an integral sheet metal back and side walls bent to define a channel longitudinally of the blade, and having an open side disposed towards said intake.

In testimony whereof I affix my signature.

WARREN E. COLLINS.
